UNITED STATES PATENT OFFICE

FRANK IZZO, OF HUNTINGTON, WEST VIRGINIA

BRAKE BEAM SAFETY IRON

Application filed September 5, 1930. Serial No. 479,956.

This invention relates to supporting means for the safety beams for the brake beams of railway cars, the general object of the invention being to provide means for firmly supporting the safety beams from the spring plank and for permitting the safety beams to be readily removed and replaced.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an end view, partly in section, of a truck frame, showing the invention in use.

Figure 2 is a top plan view of the spring plank and the beams and their supporting means.

Figure 3 is a section on line 3-3 of Figure 2.

Figure 4 is a section on line 4-4 of Figure 3.

Figure 5 is a view looking toward the inner face of one of the supporting brackets.

Figure 6 is a perspective view of one of the brackets.

Figure 7 is a view similar to Figure 1, but showing a modification.

Figure 8 is a top plan view of that form of the invention shown in Figure 7.

Figure 9 is a section on line 9-9 of Figure 8.

Figure 10 is a view similar to Figure 9, but showing another modification.

Figure 11 is a top plan view of one of the brackets shown in Figure 10.

Figure 12 is a view showing a slightly dif-

ferent form of the invention from that shown in Figures 10 and 11.

Figure 13 is a view similar to Figure 1, but showing another modification.

Figure 14 is a top plan view of that form 50 of the invention shown in Figure 13.

Figure 15 is a section on line 15-15 of Figure 14.

Figure 16 is a section on line 16-16 of Figure 15. 55

In these drawings, the letter A indicates the brake beams and the letter B the shoes, and the spring plank is shown at C, said plank being composed of two angle irons 1 connected together at their ends by cross 60 pieces 2.

The safety bars for the brake beams are shown at D and are also of angle shape in cross section. These bars D are supported from the spring plank by the brackets 3, a 65 pair of brackets supporting each bar. Each bracket is formed with a hook shaped upper end 4 which hooks over the vertical flange of the spring plank and is riveted thereto, as shown at 5. The bracket depends below the 70 plank and is formed with an enlargement 6 on its outer face which has its outer face curving downwardly to a rounded point 7 at the bottom of the bracket. A vertical slot 8 is formed in the enlargement and the bracket 75 and the upper face of the enlargement is recessed, as at 9, this recess merging into the slot 10 in that part of the bracket immediately above the enlargement. Thus an angle-shaped opening is formed in the bracket 80 through which the safety bar D passes.

A hole 11 passes transversely through the enlargement and intersects the slot 8, one end of the hole being enlarged, as shown at 12. 85 A headed pin 13 is adapted to be inserted in said hole with its head in the enlargement 12, said pin also passing through a hole in the safety bar D to hold the bar against longitudinal movement. A cotter pin 14 is passed 90 through a hole in the projecting end of the

pin and a cotter pin 15 is passed through a small hole in the bracket which intersects the enlargement 12 of the hole 11 and acts to hold the head of the pin in the enlargement. 5 Thus even if the pin 14 should become detached from the pin, the cotter pin 15 would still hold the pin 13 in position.

Thus it will be seen that each safety beam 10 D is supported by a pair of brackets from the spring plank, it simply being necessary to pass the bar through the openings in the brackets and then insert the pins 13 in the holes 11, after which the cotter pins 14 and

15 15 are inserted to hold the pins 13 in place. Thus the safety bars can be easily and quickly put in place or removed and they are firmly held in place so that there is no danger of them falling from place or being loosened by vibrations.

20 Figures 7, 8 and 9 show the invention used with a spring plank C' formed of a single piece of material, with its side edges curved upwardly, as shown. In this case, but two brackets are used, each bracket 16 being of inverted shape with its limbs depending from the plank and said limbs are formed with the enlargements, as above described. The ends of the bight portion of the bracket are bent upwardly to receive the bent-up edges of the 25 spring plank and bolts 17 pass through said bight portion and the plank with their heads lowermost and resting on the safety beam so that if the nuts should become detached, the bolts would remain in place as they are 30 prevented from dropping out of their holes by the safety beam. In other respects, this 35 form of the invention is the same as that before described.

40 In the modification shown in Figures 10 and 11, a pair of brackets 18 is used to support each safety bar from a one-piece spring plank and as shown in these figures, each bracket has its top part 19 extending horizontally and formed with a pair of outwardly 45 extending ears 20, through the perforations of which the rivets 21 pass, which fasten the brackets to the plank. The horizontally extending parts 19 engage the bottom face of the plank, as shown. The safety bar passes 50 between the lower heads of the rivets of each bracket so that the rivets will not interfere with the placing of the bar in the openings in the brackets.

55 In the modification shown in Figure 12, the bracket 18' has its horizontal part riveted to the top face of the spring plank instead of the bottom thereof, as in Figures 10 and 11. The horizontal part is also curved upwardly at its 60 point of junction with the main part of the bracket to receive the bent-up edge of the spring plank.

Figures 13, 14, 15 and 16 show the invention in use on a truck, where the spring plank 65 is located above the brake beams and the plank includes the two side angle irons. As

shown in these figures, each bracket 22 has a hook-shaped part 23 ending in a vertical flange 24, the hook-shaped part receiving the horizontal portion of the angle iron of the plank and the flange abutting the vertical 70 flange thereof. This flange is riveted to the vertical flange, as shown at 25, and a horizontal flange 26 is formed on an intermediate part of the bracket and is reinforced by the webs 27. A bolt 28 passes through the hook-shaped part 23 and the horizontal flange of an angle iron of the plank and through the flange 26, with its head resting on the safety bar which passes through an opening formed in the before described enlargement at the lower end of the bracket. Thus in this form of the invention, the safety bars are supported a distance from the spring plank so that they are properly positioned under the brake beams. 75

80 As will be seen, in all the forms of the invention, the brackets are formed with the enlargements having the openings therein through which the safety bars pass and the pins and cotter pins for holding the safety bars in position.

85 It is thought from the foregoing description that the advantages and novel features of the invention will be readily apparent.

90 It is to be understood that changes may be 95 made in the construction and in the combination and arrangement of the several parts, provided that such changes fall within the scope of the appended claims.

95 What I claim is:—

100 1. A bracket for supporting a safety bar from a spring plank, comprising means at the upper end of the bracket for attaching the same to the spring plank, an enlargement at the lower end of the bracket having an opening passing therethrough through which the safety bar is adapted to pass, said enlargement having a transverse opening intersecting the first mentioned opening and having an enlargement at one end thereof, a headed pin passing through the transverse opening with its head located in the enlargement, a pin passing through the projecting end of the first-mentioned pin and a pin passing through the enlargement of the bracket and through the enlargement of the transverse 110 hole for holding the head of the first mentioned pin in place.

115 2. In combination with a safety bar and 120 spring plank of a railroad vehicle, brackets for supporting the safety bar from the plank, each bracket having a hook-shaped upper end fitting over a part of the plank and an enlargement on the outer face of its lower end, said enlargement having an opening 125 therein to receive the safety bar, pins passing through the enlargements and the bar for holding the bar in place and bolts passing through the hook-shaped portions of the 130 spring plank and through portions of the

plank and having their heads resting upon the safety bar.

3. In combination with a safety bar and spring plank of a railroad vehicle, brackets for supporting the safety bar from the plank, each bracket having a hook-shaped upper end fitting over a part of the plank and an enlargement on the outer face of its lower end, said enlargement having an opening therein to receive the safety bar, pins passing through the enlargements and the bar for holding the bar in place, bolts passing through the hook-shaped portions of the brackets and through portions of the spring plank and having their heads resting upon the safety bar and a flange on each bracket through which the bolt passes, said flange being arranged slightly above the bar to form a space for receiving the head of the bolt.

20 In testimony whereof I affix my signature.

FRANK IZZO.
